ATTORNEYS.

UNITED STATES PATENT OFFICE.

WALTER F. BENSON, OF FORT MADISON, IOWA.

FOUNTAIN PEN.

Application filed April 23, 1925. Serial No. 25,392.

The invention relates particularly to fountain pens of self-filling type.

It is an object of my invention to provide in a fountain pen simple but highly efficient filling means adapted to compress the usual ink sack or reservoir in such a manner as to cause the greatest amount of ink to be drawn therein.

Another object is to provide in a fountain pen employing an elastic ink sack, means for collapsing the sack beginning at the rear end thereof and proceeding toward the forward or delivery end.

A further object is to provide an improved form of lever and pressure bar adapted to compress the ink reservoir, the pressure bar being carried at one end of a pressure spring and the lever having means for engaging the pressure bar and also means for engaging the pressure bar spring, the coaction of said means being operative to cause the pressure bar to first compress the rear or closed end of the sack.

With these and incidental objects in view, the invention consists of certain novel features of construction and combination of parts, the essential elements of which are hereinafter described with reference to the drawing which accompanies and forms a part of this specification.

In the drawing, Figure 1 is a longitudinal sectional view of a completely assembled pen embodying my invention and showing the ink sack in released or normal position. Figure 2 is a view of the blank from which the operating lever is formed. Figure 3 is an end view of the formed lever. Figure 4 is a bottom view of the formed lever. Figure 5 is a longitudinal section of the pen barrel with the sack compressed. Figure 6 is a perspective view of the barrel sleeve. Figure 7 is a section taken on the line 7-7, Figure 1. Figure 8 is a section taken on the line 8-8, Figure 5. Figure 9 is a plan view of the assembled pressure bar and pressure bar spring. Figure 10 is a side elevation of the same and Figure 11 is a front view of the lever pin.

As shown in the drawing the barrel 1, which may be made of rubber, metal or any other suitable material, has a sleeve or liner 2 therein and is formed about the rubber section at 3. This rubber section 3 preferably has a metal cover 4 thereover with a

threaded portion 5 to receive by thread engagement the cap 6.

The cap 6 has a tass 7 at the end thereof and preferably a ball clip 8 to serve to hold the pen in the pocket.

The rubber liner 9 is pressed into the cap 60 as shown and has a pocket 10 to receive the pen point.

The sack 11, preferably of rubber, is glued to the front end 12.

The pressure bar 13 is adapted to collapse 65 the sack, collapsing the tass end first and this pressure bar is riveted to the pressure bar spring 14, which has its opposite end formed into a lip 15 (see also Figure 10) that engages with the sleeve 2 at 16, (see 70 also Figure 6).

The lever 17 is hinged to the sleeve by the wire 18, (see Figures 5 and 11). This lever 17 is formed from a blank, as shown in Figure 2 which has the tabs 19 formed 75 back as shown in Figure 3.

The sleeve 2 is cut out as shown in Figure 6 at 20 to form a finger nail indentation for raising the lever and is also cut out as shown at 21 to allow the lever to pass thru the sleeve 80 and is formed at 22 to receive the pin or rectangular ring 18.

The rectangular ring 18 which fits in the portion 22, extends about half way into the opening 21, allowing the lever to be inserted 85 with the sleeve, the pin springing enough to prevent injury to the lever when it enters the barrel at its open end. The open end 23 of this ring holds the lever so that by springing the ring open the lever may be 90 removed after assembly if necessary.

Looking at Figure 5, it will be noted that the pressure bar is pushed downward directly by the end 24 of the lever and that the shoulder 25 of the lever also impinges 95 directly on and depresses the spring 14.

The co-action between the lever spring and pressure bar is such that the tass end 26 of the sack is first closed and the pressure point travels forwardly until the entire sack 100 is collapsed, thus preventing the pocketing of any air in the sack.

Stops 26' are provided on the pressure bar for limiting the motion of the lever 17.

While I have described my invention and 105 illustrated it in one particular design, I do not wish it understood that I limit myself to this construction, as it is evident that the

application of the invention may be varied in many ways within the scope of the following claims:

Claims:

5. 1. In a fountain pen the combination with a barrel of a pressure bar spring mounted therein, a pressure bar carried at one end of said spring, a lever mounted in hinged relation with said barrel, said lever having means for engaging said spring and also means for engaging said pressure bar, the coaction of said means being operative to depress said pressure bar, the end thereof joined with said spring being depressed 10 ahead of the free end thereof.
2. In a fountain pen the combination with a barrel, and a collapsible ink reservoir therein, of a pressure bar mounted within said barrel, a pressure bar spring adapted 20 to engage said pressure bar at one end thereof, a lever mounted in hinged relation with said barrel, means on said lever for engaging said pressure bar and means on said lever for engaging said spring, the coaction 25 of said means being operative to cause said pressure bar to compress said reservoir from the rear end thereof towards the forward end thereof.
3. In a fountain pen the combination with 30 a barrel and a compressible ink reservoir

therein, of a pressure bar spring, a pressure bar carried at one end by one end of said spring, a lever mounted in hinged relation with said barrel with one of its ends engaging said pressure bar and means at an intermediate point on said lever for engaging said spring whereby the joined end of said pressure bar and spring will be depressed against said reservoir ahead of the free end of said pressure bar. 35

4. In a fountain pen the combination with a barrel of a pressure bar spring mounted therein and having one end fixed with said barrel, a pressure bar carried at one end by one end of said spring and a forked lever mounted in hinged relation with said barrel and straddling said spring, the end of said lever being adapted to engage said pressure bar and the shoulder of the fork engaging said spring, whereby said bar will 40 be depressed when said lever is swung.

5. In a fountain pen, the combination with a barrel, of a sleeve positioned therein, said sleeve having a cut away portion to allow the passing of a lever therethru, a rectangular ring mounted in a depressed portion 50 of said sleeve and having the open end thereof extending into said cut away portion to receive the lever therein.

WALTER F. BENSON.
